JORDAN L. MOTT, OF MOTT HAVEN, NEW YORK.

Letters Patent No. 99,222, dated January 25, 1870.

BOILER-STAND.

The Schedule referred to in these Letters Patent and making part of the same.

To all whom it may concern:

Be it known that I, JORDAN L. MOTT, of Mott Haven, in the county of Westchester, and State of New York, have invented a new and useful Improvement in Boiler-Stands, of which the following is a full, clear, and exact description, reference being had to the accompanying drawing, forming part of this specification, and in which—

Figure 1 represents an elevation of a boiler-stand, constructed in accordance with my invention, and

Figure 2, a central section of the same.

Figures 3 and 4 show sectional views of detached portions of a series of stands, as nested to facilitate transportation.

Similar letters of reference indicate corresponding parts.

Stands for kitchen-boilers have been variously constructed, but with no, or very imperfect provision for nesting, when making and shipping, or transporting them in quantities, so that such articles are not only very liable to breakage, but involve heavy charges for freight, by reason of the large packing-space a series of stands occupy.

My improvement relates to boiler-stands of a pillar-form or construction, to nest which with advantage, I find it is not only necessary to find a proper dividing-line, but also, to make each part of a form that will nest with corresponding parts or portions, and that the fastening employed to hold the divided portions of each stand together, should in no ways interfere with the nesting of corresponding parts.

To this end I construct the boiler-stand, as represented in the accompanying drawing, of a hollow ta-

pering column, A, with suitable base, open at its bottom, so that a series of such columns may be nested the one within the other, as shown in fig. 3, and of an upper portion, B, made up of a ring, a, on which the boiler rests, side-ribs b, and bottom disk c, all suitably proportioned, and shaped to give to said portion B a hollow tapering character, in order that a series of such upper portions may be nested the one within the other, as illustrated in fig. 4.

In putting the parts together, to make them into stands, it is only necessary to fit the disk c over, in, or on the closed upper portion of the column A, and to connect them by a short pin, C, arranged to screw into the top of the column, so that the fastening in no way interferes with the packing, as would a long bolt, secured by nut, within or under a closed base, to the column.

Each part, A and B, of the stand being (by the form and construction herein described for them) capable of nesting within corresponding parts of other stands, space and freight are largely economized in transporting them, and the liability to breakage is reduced.

What is here claimed, and desired to be secured by Letters Patent, is—

A boiler-stand, made up in sections or portions A and B, each of a hollow and tapering form, open at their widest ends, to facilitate nesting, and secured together by a screw-bolt, C, substantially as shown and described.

JORDAN L. MOTT.
